CLAIM

The ornamental design of a combined neck and ear shade, as shown and described.

DESCRIPTION

FIG. 1 is a top plan view of a combined neck and ear shade showing our new design;

FIG. 2 is a rear elevation view thereof;

FIG. 3 is a right side elevation view thereof;

FIG. 4 is a front elevation view thereof;

FIG. 5 is a left side elevation view thereof;

FIG. 6 is a bottom plan view thereof; and,

FIG. 7 is a front, right side perspective view thereof, the head and hat shown in broken lines are for illustrative purposes only and form no part of the claimed design.
